WIRE TRANSPOSING DEVICE

Rogers Case, Orange, N. J., assignor to Trans-
adean Associates, Inc., New York, N. Y., a cor-
poration of Delaware

Application April 6, 1944, Serial No. 529,806

2 Claims. (Cl. 174—33)

1

This invention relates to a device for transposing the wires of a communication line, and constitutes a specialized improvement over the transposition device disclosed in my co-pending application Serial No. 475,286, filed February 9, 1943, issued August 29, 1944, as Patent No. 2,356,750.

A problem encountered in the erection of communication lines adapted to convey messages by the "carrier" system, is that such system requires transposition of the two paired line wires at definite minimum intervals throughout each section or division of the system. If, as is usual, transposition brackets are mounted on the line poles which support between them reaches of the communication wires, it is necessary for satisfactory "carrier" communication that the poles be spaced no further than the required minimum distance. Such exact spacing of the poles is, in many localities, extremely difficult or even impossible. In converting from the phantom system to the "carrier" system, the problem is even greater because poles have already been set and some of them are always set throughout any extended stretch of line in accommodation to local conditions rather than to proper spacing. Exact spacing under such circumstances, therefore, would require withdrawing poles which have already been set and replanting them in accordance with a requirement, which is of itself frequently difficult or impossible to meet.

The transposition device, or bracket, disclosed in my above-identified application, and which may be considered to be my standard form of bracket, consists of a single frame element from each of the opposite sides of which project two insulators, the four insulators of the bracket being mounted in approximately rectangular arrangement, and the two insulators on each side of the frame, or base, element being arranged diagonally.

A transposition bracket, such as that disclosed in my above-identified application, serves to transpose the line wires by crossing them in such manner as to preserve equal length and weight of copper in the reaches extending on both sides of the transposition point, and is arranged to separate the two wires, which normally are uninsulated, a substantial distance in their mounting on the bracket.

The object of my present invention is to provide a transposition bracket of simple construction and reduced cost, which may be used instead of my standard form of transportation bracket

2

where manufacturing or other conditions prescribe such simplicity.

In the accompanying drawings illustrative of my invention:

5 Fig. I is a plan view of my transposition device, or bracket, showing two line wires transposed by the bracket.
10 Fig. II is a view showing the transposition bracket of Fig. I partly in side elevation and partly in central vertical section.
15 The transposition bracket of my present invention is, as above noted, simple in structure. It consists primarily of a relatively thick and rigid plate, or base, 1, which desirably is a steel or iron stamping, but which may be made of any other metal or other material formed in suitable manner, provided, however, that it provides in the bracket a stiffness and tensile strength adequate to sustain the pull of a pair of tensioned line wires applied to the bracket in the manner hereinafter described. Mounted on the base 1 and projecting from the same side thereof in alignment longitudinally and horizontally of the base are a pair of identical wire-contacting and wire-training insulators 2 and 3, each of which is provided with two wire-receiving grooves, 4 and 5 of the insulator 2 and 6 and 7 of the insulator 3. These insulators may be made of glass, porcelain, or any other suitable insulating material, and may be of any desired spool form to provide specialized insulating conditions in the assembly. As shown, however, they are double-groove, spool-form insulators of the simplest structure.

20 25 30 35 40 45 50 Insulators 2 and 3 are rotatably mounted on the base 1. As shown, their mounting consists of insulator pins 8 having heads 9 and provided with threaded shanks 10 carrying nuts 11. Any suitable form of insulator pin may, however, be used, provided that it is of substantial diameter and is composed of a suitable high tensile strength material, such as high-carbon, heat-treated steel, in order to resist the stresses to which it is subjected in service. To make the insulators 2 and 3 freely rotatable on the insulator pins 8 without undue looseness, I interpose between the insulator pins and the bores of the insulators, bushing sleeves 12, and provide a slight clearance between the insulator bores and the surfaces of the sleeves. The sleeves 12 desirably are made of lead, or other suitable bearing metal.

In effecting transposition of a pair of continuously strung line wires by means of this bracket, the bracket is introduced by gathering

the slack of the wires in a reach of the line between poles and working the bracket into transposing position between the wires, utilizing the slack for transposition. In transposition of the wires, shown best in Fig. I of the drawings, one wire, designated as wire A, is worked around the insulator 2 to lie in the upper groove 4 thereof, and is also brought over and oppositely around the insulator 3 to lie in the upper groove 6 of that insulator. Similarly, line wire B is worked first around insulator 3 to lie in the lower groove 7 thereof, and is also brought over and oppositely around the insulator 2 to lie in its lower groove 5. The wires thus are symmetrically crossed within the space bounded longitudinally of the line by the diameter of the insulators at the base of their grooves and transversely of the line by the distance between the bases of the opposed grooves of the insulators. They are spaced vertically by the distance between the deepest points of the grooves in each insulator.

This, as appears in Fig. I of the drawings, effects transposition of the wires, and the overall length of the bracket from the bases of the insulator grooves being equal to the desired spacing of the line wires, the bracket tightens and accurately spaces the wires, in addition to its function of transposing them.

In this transposition bracket, two insulators only being used to effect the transposition, it is important that the insulators be rotatably mounted in order that the bracket may be brought into accurate position in a reach of the line wires between poles to equalize the distance between transposition points along the line. Because of the rotatable mounting of the insulators, it is possible to draw the bracket into such accurately spaced position by means of a "come-along," or other suitable instrument, inasmuch as the insulators may turn to relieve the binding of the wires thereon as the bracket is brought into its final desired position. Desirably, there being a close snubbing of the wires by the bracket, the bracket is mounted on the wires as close as possible to its desired final position, and as much slack as possible is provided for the lateral wire-transposing insertion of the bracket.

In spite of the relief afforded by rotation of the insulators as the bracket is drawn along the line into its final position, it is important that the base 1 and the insulator pins 8 be particularly strong and rigid by virtue of their dimensions and the material of which they are formed. This is for the reason that the insulators, projecting as they do both from the same side of the base, the strain of the wires in working the bracket into position is unbalanced and exerts a severe tendency to bend the base and to bend or break the insulator pins. By using, however, high tensile strength steel having a thickness of $\frac{1}{4}$ to $\frac{5}{16}$ inch, for example, and by using insulator pins of heat-treated high-carbon steel of combined great toughness and hardness, I am able satisfactorily to use a transposition bracket of the above-described simple structure. These exemplary dimensions assume that the bracket is designed for the standard 8-inch spacing of the paired wires of communication lines.

It is apparent from the transposing position of the wires that the insulators 2 and 3 must be of substantial dimensions with respect to the spacing of the paired wires A and B. Thus with the standard 8-inch spacing, the diameter of the insulators at the bases of their grooves should be at least $1\frac{1}{2}$ inches, and desirably is as great as is possible while leaving space between the insulators for crossing the wires. This is to permit the wires to be crossed into their transposed position in the line. In order that the wires may be separated adequately from each other in the vertical dimension, the spacing between the bases, or deepest points, of the grooves of each insulator should be not less than 1 inch, and desirably is as great as may be had without so increasing the unbalanced stresses on the insulators as to bend or break their mounting pins.

Having described a specific embodiment of a transposition bracket in accordance with my invention, it is to be understood that the invention herein is not to be strictly limited to the specific structural details as shown and described, but that changes in structure and arrangement coming within the bounds of the appended claims may be made without departing from the invention as defined therein.

I claim as my invention:

1. A wire-transposing and wire-spacing bracket for paired line wires comprising a free rigid base, and two identical wire-contacting and wire-training double-groove spool-form insulators rotatably mounted in longitudinally spaced alignment on the said base, the greatest distance between surfaces of the said two insulators at the bases of the grooves therein being conformed to the normal spacing of the paired line wires and the diameter of the insulators at the bases of the said grooves being substantial to give an angularly extended crossed position between the insulators to the two line wires trained each on opposed surfaces in aligned grooves of the said two insulators, the angularity of the crossed wires to the parallel reaches of the line defined by the groove diameter of the said insulators being sufficient for adjustment of the bracket along the line by rotation of the said insulators.

2. A wire-transposing and wire-spacing bracket for paired line wires in accordance with the definition of claim 1 in which the rotatable mounting of the insulators is provided by insulator pins passing through bores in the insulators, and bearing sleeves in the insulator bores and surrounding the said insulator pins.
